UNITED STATES PATENT OFFICE.

WILLIAM MATHER, OF MANCHESTER, ENGLAND.

APPARATUS FOR DAMPING TEXTILE FABRICS.

SPECIFICATION forming part of Letters Patent No. 546,930, dated September 24, 1895.

Application filed January 10, 1895. Serial No. 534,475. (No model.) Patented in England December 19, 1894, No. 24,715, and in France December 19, 1894, No. 243,783.

To all whom it may concern:

Be it known that I, WILLIAM MATHER, a citizen of England, residing at Salford Iron Works, Manchester, in the county of Lancaster, England, have invented certain new and useful Apparatus for Damping Textile Fabrics, (for which I have obtained Letters Patent in Great Britain, dated December 19, 1894, No. 24,715, and in France, dated December 19, 1894, No. 243,783,) of which the following is a specification.

My invention relates to apparatus for damping webs of textile fabrics, constructed and arranged in such a manner as to secure great uniformity in the distribution of the moisture over the web, as I shall describe, referring to the accompanying drawings.

Figures 1 and 2 are respectively side and front elevations of the whole apparatus. Fig. 3 is a vertical section showing the injector and nozzle, the lower part supposed to be turned one-quarter-around to show the passages.

I fix the apparatus facing a wall or screen A, down which the textile web W is drawn from above, to be moistened as it descends, and to be wound on a beam B. Steam supplied by a pipe C exerts injector action on water supplied by a pipe D, and the jet of water, mingled with the steam more or less condensed, issues by a small aperture and strikes against a cone E, placed with its apex presented toward the center of the jet.

The reference-letter D' indicates a pipe to permit the escape of the water that is discharged laterally from the nozzle, through which the steam and water first conjointly flow. By its impact on the cone the jet is distributed in spray, which has the form of a hollow cone. Generally, by means of a deflector F, I direct the lower half of this cone of spray into a cup G, while the upper half of the spray cone strikes the web W as it passes down. The

deflector F may, however, be omitted in cases where much damping is required, the whole cone of spray being then delivered on the fabric. The water caught in the cup G and water from the wall or screen are received in a tray H, whence the water can be discharged or drawn to be used again.

Having now described the nature of my said invention and the best means I know for carrying the same into practical effect, I claim—

1. In apparatus for damping fabric, the combination of an injector and nozzle, a distributing cone arranged in front of the nozzle, a deflector located between the cone and fabric to be advanced, and means for advancing the fabric, substantially as described.

2. In apparatus for damping fabric, the combination of an injector and nozzle, a distributing cone arranged in front of the jet, a deflector located between the cone and fabric to be advanced, a drip-cup arranged below the deflector and adapted to catch that portion of the spray deflected, and means for advancing the fabric, substantially as described.

3. In apparatus for damping fabric, the combination of an injector and nozzle, a distributing cone arranged in front of the nozzle, a drip-cup located in front of the nozzle, a deflector attached to the drip-cup and extending to a point substantially in line with and behind the cone, a tank located below the drip-cup, a pipe communicating with said tank and drip-cup, and means for advancing the fabric in front of the spray, substantially as described.

In testimony whereof I have signed my name to this specification, in the presence of two subscribing witnesses, this 22d day of December, A. D. 1894.

WILLIAM MATHER.
